R. E. PERKINS

SMOKING PIPE

Filed June 22, 1921

Inventor

R.E. Perkins

By *Watson E. Coleman*
Attorney

UNITED STATES PATENT OFFICE.

RICHARD E. PERKINS, OF BOSTON, MASSACHUSETTS.

SMOKING PIPE.

Application filed June 22, 1921. Serial No. 479,622.

To all whom it may concern:

Be it known that I, RICHARD E. PERKINS, a citizen of the United States, residing at Boston, in the county of Suffolk and 5 State of Massachusetts, have invented certain new and useful Improvements in Smoking Pipes, of which the following is a specification, reference being had to the accompanying drawings.

This invention relates to certain improvements in smoking pipes and it is an object of the invention to provide a novel and improved device of this general character wherein the lower or bottom portion of the bowl is surrounded by a chamber in communication with the stem and wherein said lower or bottom portion of the bowl includes a removable collar or insert of clay or other infusible material so 15 that the lower or bottom portion of the bowl is protected effectually against burning out.

Another object of the invention is to provide a novel and improved device of this general character wherein the bowl comprises 25 two sections, one of said sections constituting a removable cap, together with a sleeve arranged internally of the sections for maintaining said sections in assembled relation.

An additional object of the invention is to provide a novel and improved device of this general character wherein the bottom of the bowl is provided with an absorbent body over which the smoke is drawn and 35 whereby such smoke is freed of moisture and the like so that the smoke as it enters within the mouth of the user is substantially dry and freed of impurities.

The invention consists in the details of 40 construction and in the combination and arrangement of the several parts of my improved smoking pipe whereby certain important advantages are attained and the device rendered simpler, less expensive and 45 otherwise more convenient and advantageous for use, as will be hereinafter more fully set forth.

The novel features of my invention will 50 hereinafter be definitely claimed.

In order that my invention may be the better understood, I will now proceed to describe the same with reference to the accompanying drawings, wherein:

Figure 1 is a view partly in section and 55 partly in elevation illustrating a pipe con-

structed in accordance with an embodiment of my invention; and

Figure 2 is a view in top plan of the lower section or cap, the coacting stem being shown in fragment.

As disclosed in the accompanying drawings, B denotes the bowl or body of my improved pipe and has its lower end closed by a removable lower section or cap C. When assembled, the adjacent ends of the body B and the cap or lower section C are in close contact one with the other as illustrated in Figure 1, and are maintained in such relation through the instrumentality of an internal coupling sleeve 1.

The lower portion of the wall of the bowl is reduced in thickness from within, as at 2, whereby an annular or continuous internal stepped shoulder 3 is provided at a desired point inwardly of the lower end of the bowl or body B. The inner wall of the reduced lower portion of the wall of the bowl B is threaded and is engaged by the peripheral threaded surface of the sleeve 1, the outer end of said sleeve abutting the inner portion of the stepped shoulder 3. The sleeve 1 also extends within and has threaded engagement with the wall of a chamber 4 provided in the upper or outer face of the cap or lower section C.

Snugly fitting within the upper part of the sleeve 1 and abutting the upper portion of the stepped shoulder 3 and held frictionally in such position is an insert or collar 5 of clay or other infusible material and which insert or collar 5 is of a depth less than the major length of the portion 2 of the body or bowl B so that, when the insert or collar 5 is fitted within the sleeve 1, there will be a slight space between the bottom of the insert or collar 5 and the base of the chamber 4. The bore of the insert or collar 5 is of such configuration to be substantially in continuation of the bore of the upper portion of the bowl or body B.

The lower marginal portion of the insert or collar 5 is provided in its periphery with an annular recess or rabbet 6 whereby is provided an annular shoulder 7 surrounding the lower portion of the insert or collar 5. By having the insert or collar 5 of clay or other infusible material, the life of the pipe is materially prolonged because the insert or collar 5 serves to prevent burning out of the bowl or body B.

The lower member or cap C has its base continued by an arcuate or other extension 8 which constitutes a stem and with which is associated a mouth-piece 9. The stem 8 is provided with a draft hole 10 in communication with the chamber 4 through the bottom thereof and at a marginal portion thereof. The lower portion of the sleeve 1 overlying the induction end of the draft hole 10 is provided with a notch or recess 11 to facilitate the passage of the smoke into the draft hole 10.

The base of the chamber 4 at the axial center thereof is provided with a pocket or well 12 and which has arranged therein a filler 14 of absorbent material, so that as the smoke is drawn from the body or bowl B and through the insert or collar 5, the same will pass over such filler before it enters the draft hole 10 and thereby become freed of moisture or kindred impurities.

From the foregoing description it is thought to be obvious that a smoking pipe constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A pipe of the class described comprising a bowl, a removable cap closing the bottom of the bowl, a collar of infusible material snugly fitting within the lower portion of the bowl and spaced from the applied cap,

the lower marginal portion of the collar being provided with a peripheral rabbet, and a stem for the bowl carried by the cap and having a draft opening in communication with the rabbet of the applied collar.

2. A pipe of the class described comprising a bowl consisting of two separable sections, an internal coupling sleeve coacting with said sections for holding the same in assembled relation, a collar of infusible material snugly fitting within the sleeve and spaced from the bottom of the bowl, and a stem carried by one of the sections of the bowl and having a draft opening in communication with the bowl below the applied collar.

3. A pipe of the class described comprising a bowl including two sections, means for detachably holding said sections in assembled relation, a collar of infusible material snugly fitting within the lower portion of the upper section of the bowl and spaced from the applied lower section, a stem for the bowl having a draft opening in communication with the bowl below the collar, and an absorbent body carried by the lower section of the bowl below the collar.

4. A pipe of the class described comprising a bowl including two sections, internal means for detachably holding said sections in assembled relation, a collar of infusible material snugly fitting within the lower portion of the upper section of the bowl and spaced from the applied lower section, a stem for the bowl having a draft opening in communication with the bowl below the collar, and an absorbent body carried by the lower section of the bowl below the collar.

In testimony whereof I hereunto affix my signature.

RICHARD E. PERKINS.
